MOVING CYLINDER TYPE INTERNAL-
COMBUSTION ENGINE

Hugh E. McCallion, Roseville, Mich.

Application August 5, 1944, Serial No. 548,172

1 Claim. (Cl. 121—50)

1

The present invention relates to internal combustion engines.

Among the objects of the present invention is an engine in which the displacement is greater than in conventional engines having the same piston stroke.

Another object is an engine in which the compression is greater than in conventional engines having the same piston stroke.

Another object is an engine in which each of the reciprocating parts is balanced by a similar and equal weight part, thus making for smooth operation.

Another object is an engine in which reciprocatory cylinders are utilized not only as power producers but also as sleeve valves.

Still another object is to provide novel guide means preventing piston slap.

Still another object is an engine in which the effective piston movement is increased without increasing its speed.

Other objects and advantages will be apparent to those skilled in the art upon reference to the following description and the accompanying drawings in which

Fig. 1 is a sectional view longitudinally and centrally of the cylinders of a bank of four cylinders of an engine, shown diagrammatically.

Fig. 2 is a side elevation of a cylinder showing the operating cams in section and the cylinder and piston at one end of a stroke.

Fig. 3 is a similar view with the cylinder and piston at the other end of the stroke.

Fig. 4 is a fragmentary view showing a modified form of cam, and

Fig. 5 is a partial view similar to Fig. 1, but showing a modification.

In the drawings, an engine produced in accordance with the present invention is shown to consist of a group of cylinders and pistons arranged in the same plane around a centrally located shaft and both the cylinders and pistons reciprocable radially toward and from the shaft. Preferably, the cylinders and their respective pistons are in even number and diametrically opposite cylinders simultaneously approach or recede from each other, their pistons at the same time moving in the opposite direction.

Referring to Fig. 1, such an engine will be seen to consist of a plurality of cylinders 10, 11, 12, and 13, arranged radially about a shaft 18, and provided with pistons 10A, 11A, 12A, and 13A.

Each of the cylinders is provided with a pair of bosses or trunnions 14, which may be rollers, adapted to coact with a pair of face cams 15

and each of the pistons is provided with a pair of bosses or trunnions 16 adapted to coact with a double face cam 17, both cams 17 and 15 being fixed to a shaft 18 and in such relative position as to provide for movement of the cylinders and their respective pistons simultaneously but in opposite directions.

Also carried by and preferably integral with each of the cylinders 10 to 13 is a pair of guide members, those on cylinder 10 being designated by numeral 20, and those on cylinders 11, 12 and 13 being 21, 22, and 23 respectively.

These guide members are arranged at an angle to the axis of the cylinder, being in the four cylinder engine, at 45 degrees, and extend outwardly into suitable housings 25.

As indicated in Fig. 1, the guide members are flat members and those of one cylinder contact, in face to face relation, the guide members of adjacent cylinders, for example, one member 20 contacts guide member 22 and the other contacts member 23. These guide members, however, need not be of such proportions as to actually rub against each other at all times, but should be arranged so as to be usually a few thousandths of an inch apart. They will, therefore, preserve the angular spacing of the cylinders if, due to slight wear, lateral (with respect to cylinder axes) movement of a reciprocating cylinder should develop.

Because of the reciprocation of the cylinders 10 to 13, they may also be utilized as sleeve valves for the admission and exhaust of gases to and from their combustion chambers, and for this purpose, they are shown as being provided with ports 30 near their outer or head portions, these ports being connected to suitable manifolding (not shown).

In the modification shown in Figure 5, the pistons 110 are indicated as fixed to a spider 111 and designed to remain stationary while the cylinders 10 reciprocate. In this form the cam 17 will of course not be used. Otherwise, the design is the same as that of Figure 1.

Figure 4 illustrates a slightly different form of cam in which, instead of a channel such as at 15A in Figures 2 and 3, a single rib such as 15B is used with a pair of trunnions or cam followers 14A. The pistons, of course, may also be provided with a similar cam 17A and cam followers 16A.

The present engine design lends itself readily to the construction of engines having a greater number of cylinders than the four illustrated, as a single shaft may have several banks of cylinders.

ders surrounding it. If these banks are of four cylinders each, two, three or more banks would of course mean eight, twelve or more to an engine.

Further, without any change in basic design, more or less cylinders may be used in a group or bank and in even or odd numbers. However, if an odd number, say five, is used, two banks will be necessary to obtain all of the advantages such as balance, etc.

While the invention has been described as embodied in an internal combustion engine, it is also contemplated that the principles may be utilized in pumps and other applications without material alteration and in any application it may be found desirable to omit the guides 20 and of course their function.

Now having described the invention and the preferred embodiments thereof, it is to be understood that such invention is to be limited, not to the specific details herein set forth, but only by the scope of the claim which follows.

I claim:

In an internal combustion engine a plurality of cylinders, said cylinders numbering at least four, a shaft, said cylinders being arranged with their axes radial to said shaft and angularly equi-

spaced, pistons in said cylinders, means for reciprocating said cylinders longitudinally of their axes, and means for oppositely reciprocating said pistons, and means carried by said cylinders for maintaining their angular spacing, said last mentioned means consisting of guide members fixed to said cylinders and arranged at an angle to the axes thereof equal to one half the angle between the axes of adjacent cylinders, the guide members of adjacent cylinders slidably contacting each other.

HUGH E. McCALLION.
